UNITED STATES PATENT OFFICE.

ISAAC PHILLIPS, OF BURLINGTON, IOWA.

IMPROVEMENT IN SMUT-MACHINES.

Specification forming part of Letters Patent No. 40,639, dated November 17, 1863.

To all whom it may concern:

Be it known that I, ISAAC PHILLIPS, of Burlington, in the county of Des Moines and State of Iowa, have invented certain new and useful Improvements in Smut-Machines for Cleansing Grain; and I do hereby declare that the following is a full, clear, and exact description thereof, reference being had to the accompanying drawings and the letters and figures marked thereon, which form part of this specification.

In the said drawings, which are hereunto annexed, Figure 1 represents a vertical section of my invention through the center thereof; Fig. 2, a horizontal section at the line *x* in Fig. 1; Fig. 3, a similar view at the line *y* in Fig. 1, and Fig. 4 a perspective view of one of my improved beaters for cleaning the grain.

The object of my invention is to obtain a smut-machine for cleansing and purifying wheat and other grain, and removing and separating therefrom all impurities of whatever kind, preparatory to grinding said grain into flour, which shall be simple and cheap in its construction, and at the same time effect the purpose of such a machine in a much more perfect manner than has hitherto been done.

It also consists in so constructing said machine that it will perform its work equally well, whether the vertical shaft propelling said machine be revolved in one direction or the other—namely, to the right hand or left.

To enable those skilled in the art to understand how to construct and use my invention, I will now proceed to describe it with particularity.

A in the annexed drawings represents a cross section of a shaking screen, over which the grain passes before entering into the cleansing or beating apparatus, being provided with two screens, *a'* and *c'*, and a return-board between them, *b'*. This screen is vibrated or shaken by means of a small crank upon the upper end of the shaft *B*, to which it is attached, and which is revolved by means of a belt passing around the drum *B'* and the power-shaft propelling the machine.

C represents a vertical perforated and corrugated cylinder, of sheet-iron or other suitable metal, within which the apparatus for cleaning the grain is situated, which appara-

tus consists in the following described parts and devices:

E and *F* represent two devices for beating the grain, being made of cast-iron or any other suitable metal, whose construction is clearly shown in Fig. 4. The said cylinder has a closed top, at the center whereof there is a bearing for the upper end of the vertical shaft *D*, whose lower end rests in a suitable bearing in the lower frame of the machine, as shown in the drawings. The said cylinder has also an opening through the top to admit the grain within it, which opening is surrounded by a close passage (marked *P* in the drawings) extending upward and opening into the box *G*. The interior surface of the top of the cylinder is corrugated, as shown, as also is the upper surface of the beaters *E* and *F*, which are fixed upon the revolving shaft *D* and revolve with it, said shaft being driven by means of a belt passing around the drum *D'*, in the same manner as the shaft *B* is driven. About half-way down the cylinder it is provided with an annular ledge, projecting inward, (marked *e*), whose lower surface is also corrugated; and fixed upon the shaft *D*, just above said annular ledge *e*, is the bar *a*, provided with forked ends, as clearly shown in Fig. 3, and just below said annular ledge *e* is the beater *F*, constructed and operating in the same manner as *E*.

b represents a spout or chute whereby the grain, after passing through the beaters, passes out from the cylinder *C*.

Arranged upon the shaft *D*, below the above-described beating device, is a revolving fan, *J*, inclosed in a tight circular box, for the purpose of inducing currents of air to pass through the grain and take out and carry off the impurities detached and separated therefrom by the above-described apparatus.

H, *I*, and *P* are pipes or flues through which the currents of air induced by the operation of the fan *J* pass. The flues *I* open, respectively, into two horizontal passages arranged on each side of the fan-box, which lead out over the smut-box *K*, into which they open downwardly.

L and *M* represent two openings from the fan-box to provide for the escape of air therefrom when the fan is in motion, and by closing either one and leaving the other open the

fan may be revolved either way with equal facility and effect. It will be observed also from the configuration of the perimeter of the beaters E and F that they may be revolved in either direction also with the same effect, and the forked arm *a* is intended to facilitate this arrangement, as hereinafter described.

The lower journal or bearing in which the shaft D revolves is constructed as follows: The journal box D is removable and adjustable, being placed in a suitable recess in the timber or beam which supports the shaft, and confined in any required position by means of a set-screw, *e*, or any other suitable device. By this arrangement, as the shaft D is always drawn by the driving belt in one direction, when that side of the bearings or journal box becomes worn, so as to render the belt loose upon the drums and liable to slip down, the difficulty may be obviated by moving the adjustable bearing *d* around so as to present an unworn part to the frictional action of the shaft.

Having thus described and shown the construction of my improved smut-machine, I will now proceed to describe the operation thereof, supposing the shafts B and D, with their attachments, to be revolving. As the grain falls upon the shaking screen A, it passes through the upper screen, *a'*, and falls upon the sloping board *b'*, which carries it back to the end of the screen, where it falls upon the screen *c'*, through which it passes, and goes out from the screen through the spout *s* into the scouring apparatus, the beaters E and F and the forked arm *a* in the meanwhile revolving rapidly. The grain falling upon the upper surface of E is scoured between it and the corrugated surface above, and, passing down, the projecting sides of E and the corrugated interior surface of the inclosing cylinder again scour the grain, which falls upon the ledge *c*, whence, by the revolving arm *a*, it is gathered and thrown upon the beater F, by which the same process is repeated, and the grain falls to the bottom of the cylinder and passes out through the chute *b*, perfectly clean and pure.

In the meantime the operation of the fan J, forcing the air out at the outlet M, induces a current of air or a draft in the direction of the black arrows up through the flue H and through perforations in P, just beneath the spout *s*, through which the grain passes from the screen into the scouring apparatus, as shown, and also through the spout *b* and the apparatus in E and F and the perforations in the cylinder C, all said currents passing up through the falling grain, whose course is indicated by the red arrows, into the chamber G, separating and bearing the filth and smut away from the grain, and thence passing down through the flues I and the horizontal passages aforesaid, into which said last-mentioned flues open, depositing the smut in the chamber K, and passing in the direction of the said black arrows into the fan-box, to be driven out through the outlet M by the revolution of the fan, as aforesaid. By closing the outlet M and opening the valve at L, and revolving the fan in the reverse direction, the air is forced out at L with exactly the same result, and by the peculiar arrangement of the parts within the cylinder C the reverse motion of the shaft will produce exactly the same effect upon the grain.

Having thus described the construction and operation of my invention, I will now specify what I claim as new and desire to secure by Letters Patent:

1. Providing the cylinder C with one or more ledges, *c*, in combination with the beaters E and F and the arm *a*, arranged and operating substantially as herein set forth and described.

2. Providing the beaters E and F with the re-entrant faces *m n*, when used in combination with the ledges *c* and the pronged arm *a*, as and for the purposes herein specified and shown.

ISAAC PHILLIPS.
